UNITED STATES PATENT OFFICE

138,100

DESIGN FOR A WALLET

Emil Carl Renz, Dedham, Mass., assignor to Knight Leather Products, Inc.

Application July 3, 1943, Serial No. 110,597

Term of patent 14 years

(Cl. D87—3)

To all whom it may concern:

Be it known that I, Emil Carl Renz, a citizen of the United States, residing at Dedham, in the county of Norfolk and State of Massachusetts, have invented a new, original, and ornamental Design for Wallets, of which the following is a specification, reference being had to the accompanying drawing, forming a part thereof, in which:

wallet showing my new design, in unfolded position.

I claim:

The ornamental design for a wallet, as shown.

EMIL CARL RENZ.
